SIGNAL

Filed May 25, 1936

UNITED STATES PATENT OFFICE

2,128,800

SIGNAL

Joseph A. Chinskey, Baltimore, Md.

Application May 25, 1936, Serial No. 81,759

1 Claim. (Cl. 177—329)

This invention relates to combined signal devices and flash lights and has for an object to provide an improved portable lamp of this character particularly adapted to the utilization of tubes containing a gas such as neon in which an electrical discharge causes luminescence.

A further object of the invention is to provide a compact device of this character which will be selectively operable to display a neon danger signal such as danger or stop, or to be used as an ordinary flash light.

A further object is to provide a device of this character which will be formed of a few strong simple and durable parts, which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

25 In the accompanying drawing forming part of this specification,

Figure 1 is a longitudinal sectional view through a combined signal and flash light constructed in accordance with the invention.

30 Figure 2 is a cross sectional view taken on the line 2—2 of Figure 1.

Figure 3 is a longitudinal sectional view through the device with parts in end elevation.

35 Figure 4 is a detail end elevation showing the means for applying and removing the flash light lens to replace a burned out bulb.

Figure 5 is a fragmentary end elevation showing the switch for selectively controlling the danger signal light or the flash light.

40 Figure 6 is a diagrammatic view showing the electrical connections of the device.

Figure 7 is a diagrammatic view showing a modified form of electrical connections.

Referring now to the drawing in which like characters of reference designate similar parts in the various views, 10 designates a casing having the bottom closed by a cap 11, one edge of which is provided with a recess 12, as best shown in Figure 3, to receive a projection 13 on the casing, thus forming a hinge upon which the cap may be swung open against the pressure of a spring pressed pin 14 disposed in the casing diametrically opposite the projection 13. The top of the casing is flared at the sides, as also best shown in Figure 3, and is provided with an

opening 15 to receive a reflector 16 and a lens 17 for housing a flash light bulb 18. A retaining ring 19 removably secures the lens in place to permit replacement of a burned out bulb. Oppositely disposed pins 20 are secured to the top of the casing and have restricted necks to work in bayonet slots 21 formed in the ring to removably secure the ring in place.

A substantially U-shaped plate 22 of insulating material is secured to the back of the casing by 10 means of screws 23, as best shown in Figure 2. A conductor bar 24 is secured to the inner face of one leg of the plate and a conductor bar 25 is secured to the inner face of the other leg of the plate. Leaf springs 26 and 27 carried by the 15 bars removably secure a battery cell 28 in the casing and electrically connect the poles thereof to the bars 24 and 25. Similar springs 29 and 30 removably secure a battery cell 31 in the casing above the battery cell 28.

A transformer 32 is secured to the legs of the plate 22 above the battery cells, and is equipped with a vibrator 33 to alternately make and break the primary of the coil whereby high tension alternating current is induced in the secondary 20 winding of the coil.

A step up transformer 34 is secured to the legs of the plate 22 in superposed relation to the transformer 32 directly in rear of a shield 35 which is substantially U-shape in cross section, 30 as best shown in Figure 3. The shield is disposed in rear of an opening 36, as best shown in Figure 2, formed in the front wall of the casing near the top thereof. A transparent pane 37 closes the opening and is held in position in a 35 rabbit 38 in the casing by pressure of the shield. It will be observed that the shield is formed of spring metal and that the legs are terminally directed in a reverse direction to form a channel which receives the sides of an oblong frame 39 40 whereby the shield is confined snugly in place and in turn holds the pane 37 in place.

As shown in Figures 3 and 5 a substantially U-shaped switch arm 40 is pivoted on a pivot pin 41 secured to one of the legs of the U-shaped plate 45 22, one end of the switch arm being directed outwardly to form a grip 42 which passes through an opening 43 for rocking the switch to either of its two closed positions or to neutral position. Switch contacts 43' and 44 are disposed on opposite sides of the switch arm and are selectively engageable by the switch arm to close the circuit to the flash light or to the neon light about to be described.

A neon light 45 is disposed within the enclosure 55

of the shield 35 and may be secured to the pane by glass lugs 46 or may be otherwise secured in position. The neon light is of such form as to constitute a signal word such as "stop" or 5 "danger."

The electrical connections of the device are best shown in Figure 6 in which it will be seen that conductor wires 47 and 48 connect the terminals of the flash light 18 with the battery cells 10 and with the switch contact 43 respectively. The primary winding of the transformer 32 is connected by conductor wires 49 and 50 to the battery cells and to the switch arm 40 respectively. The secondary winding of the transformer 15 32 is connected by conductor wires 51, and 52 to the primary winding of the transformer 34. The secondary winding of the transformer 34 is connected by conductor wires 53 and 54 to the terminals in the neon tube so that the high 20 tension alternating current from the transformer 34 will create luminescence in the neon gas in the well known manner when the switch arm 40 is moved to engage the switch contact 44.

In some instances it may be desirable to dispense 25 with the step up transformer 34 and to employ merely a single transformer 55 similar to the transformer 32 in connection with battery cells 56 for supplying the neon light 57 with high

tension alternating current as indicated diagrammatically in Figure 7. The rest of the electrical connections for supplying the flash light 58 with current are the same as previously described.

From the above description it is thought that the construction and operation of the invention 5 will be fully understood without further explanation.

What is claimed is:

In a portable flashlight unit, a casing of substantially rectangular cross section providing a wide front wall to display a warning signal, a substantially U-shaped plate in the casing removably secured to the rear wall of the casing and having parallel legs extending along the ends of 15 the casing toward the front wall of the casing, a battery in the casing carried by said legs, a transformer secured to said legs above the battery, a make and break device for the transformer, a window pane in the front wall of the 20 casing, a reflector in rear of said pane, a neon light in the casing between the pane and the reflector, circuit wires connecting the transformer to the neon light, circuit wires connecting the battery to the transformer, and a switch on 25 the casing controlling the flow of current to the last named circuit wires.

JOSEPH A. CHINSKEY.
